UNITED STATES PATENT OFFICE.

FRED W. POWERS, OF CHICAGO, ILLINOIS, ASSIGNOR TO THE POWERS REGULATOR COMPANY, OF CHICAGO, ILLINOIS, A CORPORATION OF ILLINOIS.

PILOT-BURNER CONTROL.

Application filed March 6, 1922. Serial No. 541,606.

To all whom it may concern:

Be it known that I, FRED W. POWERS, a citizen of the United States, and resident of Chicago, in the county of Cook and State 5 of Illinois, have invented certain new and useful Improvements in a Pilot-Burner Control, of which the following is a specification.

My invention relates to regulating devices and particularly to a device adapted to 10 reduce the quantity of gas received for the pilot burner.

In all liquid fuel burners arranged for automatic control it is customary to employ a pilot burner, the function of which is to effect relighting of the main burner whenever necessary. Naturally therefore, the pilot must remain in operation at all 15 times. In order to effect the relighting function with certainty a pilot of substantial size must be provided and this entails the consumption of a considerable amount of gas which however is unnecessary at those times when the main burner is shut off.

An object of my invention is to provide 20 means whereby the interruption of the supply of fuel to the main burner serves to effect a shut off of the supply of fuel to the pilot burner, with the exception of a small amount necessary to maintain the burner 25 in operation. To that end, I provide a gas shut-off valve adapted to be maintained in open position by pressure of fuel or air as supplied to the main burner together with 30 a by-pass around the valve, through which by-pass a sufficient quantity of gas is constantly delivered to maintain the pilot burner in operation.

The invention will be more readily understood 35 by reference to the accompanying drawings, in which:

Figure 1 is a diagrammatic view showing an arrangement such as contemplated by me and,

Figure 2 is an enlarged sectional view 40 through a gas control valve adapted to be employed in connection therewith.

In the drawings a conventional form of heater is indicated at 10, into which a burner 45 11 projects in the usual manner. A motor 12 is employed to supply fuel to the burner by means of the pump 13 and the conduit 14. Air for use in assisting combustion and for breaking up the liquid fuel is supplied 50 by the pump 15 and conduit 16.

A pilot burner is indicated at 17 this being preferably of the Bunsen type. Gas is supplied to the burner 17 through the conduit 18.

A gas control valve 19 is located in the pipe 18 it being mounted in a casing 20. Within the casing is a passage 21, around the valve the effective size of the passage or by-pass being varied at will by means of a restricting valve 22, in the form of a set screw. Secured to the valve casing 20 is a frame 23 containing a bellows 24 one side of which is anchored to the frame and its other side is abutted against a plunger 25 which contacts the valve 19. A small bellows 26 is provided to eliminate the necessity for a packing gland around the plunger 25. A spring 27 tends to close the valve 19, it being shown in open position in Figure 2.

A branch pipe connected by a T to the pipe 16 serves to place the interior of the bellows 24 in communication with the air pressure developed by the motor 15 such pressure tending to expand the bellows and 60 to open the valve 19 by overcoming the force exerted by the spring 27.

The operation is as follows:

Assuming that the main burner is not being supplied with fuel and air due to shutting off of the motor 12, the valve 19 will be closed and a very small quantity of gas will be constantly delivered to the pilot burner through the by-pass 21, the amount being only that sufficient to keep the burner 65 in operation. Whenever, due to thermostatic control or otherwise the motor is energized, air pressure will be developed which as an incident of its main purpose, will serve to expand the bellows 24 and open the gas valve 70 19 allowing a larger quantity of gas to pass to the pilot burner 17. Thus the main burner will be ignited with certainty. Upon reversal of the conditions stated the amount of 75 gas supplied to the pilot burner will be reduced to a minimum.

It is apparent that in an arrangement such as described the desired result might be effected in the same manner by employing the liquid fuel pressure instead of the air 80 pressure and in the accompanying claims the terms employed should be construed as covering this and similar modifications.

I claim:

1. In a device of the class described the 85

- combination of a fuel burner, a pilot burner, a conduit for delivering gas to the pilot burner, a conduit for delivering fuel to the fuel burner, a conduit for delivering air 3 under pressure to the fuel burner, a valve in said gas conduit for limiting the supply to the pilot burner, means providing a by-pass for maintaining a constant reduced supply of gas to the pilot, and means operable by 10 said air under pressure for moving said valve.
2. In a device of the class described, the combination of a fuel burner, means for supplying fuel and air under pressure to 15 said burner, a gas pilot burner, a valve for controlling said pilot burner, means providing a constantly open passage for gas to said pilot burner irrespective of the position of said valve, and means operable by 20 said pressure producing means for the fuel and air for maintaining said valve in open position and for permitting the closing of said valve on the interruption of the pressure of fuel and air.
- 25 3. In a device of the class described, the combination of a fuel burner means for sup-
- plying fuel and air under pressure thereto, a pilot burner, a valve for controlling the supply of gas to said pilot burner, means providing a constantly open passage around 30 said valve to said pilot burner, and means operable by the pressure of fuel or air for opening said gas valve whereby a relatively large volume of gas is supplied to the pilot burner and for closing said valve upon the 35 interruption of the pressure of fuel or air and thereby interrupting the supply of gas to the pilot burner through said valve.
4. In a device of the class described, the combination of a fuel burner, a pilot burner, 40 a conduit for delivering gas to the pilot burner, means for delivering fuel and air under pressure to said fuel burner, a valve in said gas conduit, means providing a by-pass around said valve whereby a constant 45 reduced supply of gas is furnished to said pilot burner, and means operable by the air pressure for moving said valve.

Signed at Chicago, Illinois, this 28th day of February, 1922.

FRED W. POWERS.
